US00D833643S

(12) **United States Design Patent** (10) **Patent No.:** **US D833,643 S**
(45) **Date of Patent:** **** Nov. 13, 2018**

(54) **INTEGRATED LADDER TRAY HOOK**

(71) Applicant: **Tricam Industries, Inc.**, Eden Prairie, MN (US)

(72) Inventors: **Joseph P. Foley**, St. Paul, MN (US); **Benjamin P. Williams**, Chaska, MN (US)

(73) Assignee: **Tricam Industries, Inc.**, Eden Prairie, MN (US)

(**) Term: **15 Years**

(21) Appl. No.: **29/609,951**

(22) Filed: **Jul. 7, 2017**

(51) LOC (11) Cl. **25-04**

(52) U.S. Cl. **D25/68**
USPC .....

(57) **CLAIM**

We claim the ornamental design for an integrated ladder tray hook, as shown and described.

DESCRIPTION

FIG. 1 is a perspective view of an integrated ladder tray hook according to the invention.

FIG. 2 is a top view of the integrated ladder tray hook according to the invention.

FIG. 3 is a front view of the integrated ladder tray hook according to the invention.

FIG. 4 is a bottom view of the integrated ladder tray hook according to the invention.

FIG. 5 is a left side view of the integrated ladder tray hook according to the invention; and,

FIG. 6 is a right side view of the integrated ladder tray hook according to the invention.

The broken lines shown in the drawings are for the purpose of illustrating environment and form no part of the claimed design.

1 Claim, 3 Drawing Sheets
